UNITED STATES PATENT OFFICE

2,186,823

TUNING SYSTEM

Donald R. De Tar, Stratford, Conn., assignor to
 General Electric Company, a corporation of
 New York

Application July 1, 1937, Serial No. 151,432

3 Claims. (Cl. 250—20)

My invention relates to automatic tuning systems for high frequency apparatus and more particularly to control means for such tuning systems. It has reference to that class of automatic tuning systems which is commonly employed in radio receivers to effect tuning of the receiver to a desired frequency in response to a switching operation, as in response to the pressing of a button. Commonly in such systems a plurality of buttons, or control keys, are employed, each corresponding to a particular frequency and means are employed automatically to tune the receiver to the frequency corresponding to the particular control key operated.

One of the objects of my invention is to provide certain mechanical improvements in such systems whereby the control of the tuning system is facilitated and rendered more efficient.

Another object of my invention is to effect certain improvements in the driving means for the tuning device to facilitate manual tuning of the receiver, notwithstanding the drive connection between the motor and tuning device. One object of this improvement is to avoid drag 25 of the motor when the tuning device is manually driven.

Certain other objects of my invention pertain to improved stopping means for the tuning device when the desired condition of resonance to a desired frequency is attained, and to an improved assembly of keys for controlling the motor.

The novel features which I believe to be characteristic of my invention are set forth with particularity in the appended claims. My invention itself, however, both as to its organization and method of operation together with further objects and advantages thereof, may best be understood by reference to the following description taken in connection with the accompanying drawings in which Fig. 1 represents an embodiment of my invention, Figs. 2, 3 and 4 illustrate details, Fig. 5 indicates a modification and Fig. 6 a detail.

Referring to Fig. 1 of the drawings, I have shown at 1 therein a tuning device which may comprise the tuning condenser of an ordinary radio receiver. The shaft of this condenser is provided with a pulley 2 by means of which it is driven. At 3 I have conventionally indicated a motor for driving the condenser 1, this motor having a shaft 4 upon which is mounted a gear 5. This gear meshes with a second gear 6 which is mounted on the same shaft with a smaller gear 8, the latter of which meshes with

the ring gear 9 of an epicyclic gearing system. This system includes, in addition to the ring gear 9 a sun gear 10, and an intermediate gear 11. This intermediate gear 11 comprises the driven arm of the epicyclic system and is mounted upon a shaft 12 carried by the end of an arm 13, the opposite end of which is mounted on the shaft of a pulley 14, this pulley being mounted coaxially with the sun gear 10, and being belted to the pulley 2.

The construction of the epicyclic gearing system is such that sufficient friction exists between the gears 9, 10, and 11 so that these elements when driven by the motor through gear 8 remain stationary relative to each other, that is, the three gears rotate as a single unit about the axis of gear 10. Gear 11 and shaft 12 are thus carried about the axis of gear 10, thereby driving the pulley 14 at a speed determined by the ratio of the external diameter of ring gear 9 to the diameter of gear 8.

If it be desired to tune the receiver manually by rotation of knob 21, the drag of the motor and friction in the gear chain between ring gear 9 and the motor is such that ring gear 9 remains stationary. Rotation of the knob and gear 10, therefore, causes intermediate gear 11 to travel around the inner periphery of ring gear 9 and thus rotate pulley 14 at a much reduced speed.

In this way the motor may be driven by either the knob 21 or the motor 2, each operating freely and practically independently of the other and at the same time no shifting or transferring of gears is necessary, both the knob and the motor being continuously in driving relation with the condenser.

While I have shown the various gears of toothed type, it will, of course, be understood that these may be of the friction type to reduce backlash etc., and that the various other mechanical expedients now known to the art to insure the smooth and free operation of the system may be employed.

The motor is controlled by an electrical control system comprising an assembly 16 of push buttons, or control keys, of which five are shown in the drawings. Of course many other control keys may be incorporated in this assembly. Of these keys, keys 17 and 18 and any additional keys, not shown, which may be included correspond respectively to each of the different frequencies to which the receiver is to be tuned. The key 19 is one which is operated when it is desired to tune the receiver manually as by manipulation of the handle 21. Key 20 is employed

to turn the receiver off when it is not in use, and key 22 is employed for energization of the motor if desired during the manual tuning operation.

5 These keys are all mounted in a unitary assembly comprising parallel plates 23 and 24, each of which is slotted to receive the different keys. The keys are bifurcated at the inner ends thereof to receive springs 25, the inner ends of 10 which engage the plate 23, these springs operating to bias the keys to the left as shown in the drawing, that is, to their normal position.

Key 22 is one which when released by the operator always returns to its normal position. 15 The remaining keys when pressed by the operator remain in the operated position, being locked in that position by a locking member 26. This locking member comprises a plate which extends throughout the length of the key assembly, the 20 outer edge being supported as at 27 in small openings in the plate 24 and the inner edge being bent downwardly to engage in notches 28 in the upper edge of the different keys, plate 26 being biased downward against the keys by means of 25 a spring 29. Key 17 is shown in its operated position and plate 26 is shown resting in the left-hand notch 28 of that key, thereby locking the key in that position. If now key 18 be pressed, as member 26 rides from one notch 28 of this 30 key to the other, it is raised sufficiently to release key 17. In this way the operation of any key except key 22 releases any other key which may be locked in its inner position.

At 31 I have shown a relay having an armature 7 which operates a plurality of pairs of contacts 32, 33 and 34, these contacts being included in certain circuits of the motor and receiver later to be described. This armature is also provided with a projection 36 which when the armature is attracted lies in the path of movement of two wings 37 on the gear 5 of the reduction drive gear train, thereby preventing rotation of that gear when the relay 31 is energized. One side of this relay is connected to one side of a suitable source of operating potential 46 and the other side is connected to the plate 23 and thence through the receiver keys 17, 18 corresponding to the different frequencies and contacts 38, 39 co-operating therewith to the respective contacts 38', 39' of a commutator 40. This commutator comprises a substantially semi-circular plate 41 having a plurality of concentric slots 43, in which slots the different contacts 38', 39', etc. are mounted. Cooperating with these contacts is a movable contact 42 which is mounted within an insulating block 44 carried by an arm 45 which is mounted on the shaft of the tuning device.

Contact 42 is connected to one side of the source of potential 46 and to ground, if desired, 60 through the arm 45. When this arm engages a stationary contact corresponding to a push button which has been pressed, a circuit is completed through relay 31. With the apparatus in the 65 position shown in the drawings, this circuit extends from one side of the source 46, through arm 45, movable contact 42, stationary contact 38', conductor 50, contact 38 which is engaged by key 17, key 17, member 23, conductor 52, winding of relay 31, and thence back to the other side of the source 46. The armature of relay 31 is therefore attracted and its projection 36 operated into the path of movement of wings 37 of the gear 5, thereby stopping this gear and hence the tuning device 1. At the same time contacts 32 70 of relay 31 interrupt the energizing circuit of the 75

motor, this circuit extending from one side of the source 46 through contacts 32 of the relay, contacts 53 of key 20, contacts 54 of key 19, and thence through motor 3 to the opposite side of source 46. At the same time contacts 33 of the relay interrupts the ground connection of the automatic frequency control bus of the receiver. This bus may, for example, comprise the conductor over which unidirectional potential is supplied from the detector of the receiver to the means employed for controlling the frequency of the oscillator. Removal of this ground by contact 33 places the automatic frequency control device in normal operation. By means of contacts 34 a ground connection is removed from the silent tuning conductor of the radio receiver. This conductor may extend, for example, to the grid of the first audio stage of the receiver thereby to silence the receiver when the conductor is grounded. By reason of these operations the receiver is in its normal operating condition.

Let us assume now that it be desired to tune the receiver to a frequency corresponding to the key 18. Key 18 is pressed inward, thereby, through locking device 26, releasing key 17. 25 Upon release of key 17, relay 31 is deenergized and its armature 36 moved out from engagement with wing 37, thereby permitting rotation of the gear 5. At the same time contacts 32, 33 and 34 are closed, contacts 32 completing the circuit 30 of the motor, whereby the motor operates to drive the tuning condenser. Contacts 33 ground the automatic frequency control conductor and contacts 34 ground the silent tuning conductor, thus silencing the receiver during the tuning operation. When the arm 45 has been rotated until contact 42 engages stationary contact 39', relay 31 is again energized, which again stops the tuning condenser, deenergizes the motor and, by reason of its contacts 33 and 34, restores the receiver to its normal operating condition.

In case the motor operates the condenser in such a direction that arm 45 moves away from contact 39', rather than toward it, then such movement continues to the limit of the range 45 of movement of the condenser at which time reversing switch R is operated by one or the other of two arms 7, mounted on the condenser shaft. This switch alters the energization of the motor and causes it to reverse its direction of rotation. 50 Arm 45 then moves until engagement is made at contact 39' where the motor is deenergized.

If it be desired to tune the receiver manually, as by rotation of knob 21, as may be the case when it is desired to tune the receiver to a frequency for which no button 17, 18 is provided, then the manual tuning button 19 is pressed inward. This button, by means of its contacts 54, deenergizes the motor. By means of contacts 55, it removes ground from the silent tuning conductor and thus permits normal response of the receiver. Its contacts 56 ground the automatic frequency control conductor through contacts 33 of the relay and thus disable the automatic frequency control system of the receiver. The receiver may now be tuned manually by rotation of the knob 21.

It will be observed, however, that the knob 21 is connected to the tuning condenser shaft through a drive system of considerable step-down ratio. Accordingly if a large movement of the condenser be necessary to tune the receiver to a desired station by means of the knob 21, the operation may become laborious. In this case the operator may press button 22 which bears the 75

legend "motor". This button, by means of contacts 51, energizes the motor, which drives the tuning condenser. When the tuning condenser has reached the position where the receiver is tuned approximately to the frequency desired, as may be noted by the position of the index (not shown) upon the dial of the receiver, the operator may then release the motor button and complete the tuning operation manually by rotation 10 of knob 21. As previously stated, motor key 22 is not locked in its inner position, but immediately returns to the position shown under its bias when released by the operator.

When it is desired to turn the receiver off, the operator presses the "off" button 23 which, by means of its contacts 58, deenergizes the receiver and, by means of its contacts 53 opens the motor circuit. The receiver may now, again, be turned on by pressing the manual button or any 20 of the frequency selecting buttons 17, 18, etc.

It will be observed that the rotation of the condenser is stopped by movement of projection 36 of the relay armature in the path of movement of wings 37 of the gear 5 thereby practically instantly stopping the condenser. The drive ratio between gear 5 and the tuning condenser shaft is, of course, high, with the result that the tuning device is stopped accurately in the desired position. The small movement of the gear 5 after 30 energization of relay 31 is not sufficient to operate the condenser sufficiently to affect the accuracy of tuning to any appreciable degree. Were no other means provided, however, the entire inertia of the motor armature would be expended 35 upon the relay armature, thus subjecting it to stress which might necessitate its heavier construction than would otherwise be necessary. To avoid such heavy construction of the relay 31, a friction clutch is included between the gear 5 and the motor shaft. The construction of this 40 clutch is best shown in Fig. 2, in which the shaft of the motor is indicated at 4. Upon this shaft are mounted two collars 60 and 61, between which is mounted the gear 5, having the wings 37 45 and a spring 63, the spring pressing the gear 5 against the collar 60. Accordingly, when rotation of the gear 5 is stopped by movement of the armature 36 between wings 37, shaft 4 of the motor may continue to rotate until the energy stored 50 therein is consumed in friction between the surfaces of gear 5 and collar 60, these surfaces, of course, slipping relative to each other and acting as a brake, tending to stop the motor.

Figure 3 is a detailed sectional view showing the manner of attachment of the stationary contacts 38, etc., to the plate 41. It will be seen that these contacts comprise the head of a screw-threaded member 70 which passes through a non-conducting collar or bushing 72 in the plate 55 and cooperates with a threaded bore in a member 73 back of the plate. By tightening this screw the bushing is rigidly secured in place upon the plate.

Fig. 4 shows in detail the construction of the block 44 carried by the arm 45. This block is of non-conduction material having surfaces adjacent to the plate 41 of V shape, the contact 42 being mounted in a slot at the vertex of the V. Thus the inclined surfaces of the block adjacent 70 to the contact 42 permit the block and the contact to ride smoothly over the rounded surfaces of the stationary contacts with which it cooperates. This block is provided with oppositely extending arbors 73 which pivot in the wings 37 of 75 the arm 45, so that it rocks about these pivots in

accordance with the slot in which the stationary contact with which it engages is mounted.

The control key assembly 15 of the receiver may be mounted in the receiver in any suitable way as by non-conducting supports attached to members 23 and 24. Preferably it may be arranged on the panel of the receiver beneath the usual dial the keys 17 to 22, etc. projecting through the panel. This assembly which may be mountable and demountable as a unit, includes, as seen from the above description, all of the controls necessary for operation of the receiver, including not only the frequency selecting buttons but also the "off" button and the additional buttons 19 and 22 for control of the motor and certain receiver circuits in manually tuning of the receiver.

In Figs. 5 and 6 I have shown a modification of the condenser drive in which the ratio of drive by means of the knob automatically shifts after movement of the knob through a predetermined range. In this figure the sun gear 10 is replaced by a conical surface 74 on the shaft on which the knob is mounted. The intermediate gear comprises the three balls 75 arranged in a race 76 which may be made integral with the pulley from which pulley 2 is driven. The outer ball race 78 is provided with a gear 79 which may cooperate with gear 8 of Fig. 1. Race 76 is provided with a cam 80 better shown in Fig. 6 and finger 81 which cooperate with a finger 82 on the shaft of the knob.

As thus arranged during initial movement of the knob the drive is exactly as described in connection with Fig. 1. After rotation of the knob in excess of approximately one revolution finger 82 engages cam surface 80 thereby moving the shaft to the right against spring 83 causing balls 75 to move inward sufficiently to break the drive connection therethrough. Upon further movement of the knob pulley 77 is driven by fingers 81 and 82 at the same speed as the knob.

While I have shown a particular embodiment of my invention, it will, of course, be understood that I do not wish to be limited thereto, since different modifications both in the circuit and in the instrumentality employed may be used without departing from my invention. I contemplate, by the appended claims, to cover any such modifications, as fall within the true spirit and scope 50 of my invention.

What I claim as new and desire to secure by Letters Patent of the United States, is:

1. In a high frequency receiver having a tuning device, the combination of a motor for driving said tuning device, a unitary control key assembly comprising a plurality of keys, certain of said keys corresponding to respective frequencies to which said receiver may be tuned, and other of said keys corresponding to certain other operations to be effected, means automatically responsive to operation of any of said certain keys to energize said motor until the receiver is tuned to a frequency corresponding to that one of said certain keys operated, and then to deenergize said motor, means responsive to operation of one of said other keys to energize said motor during the entire time during which said key is operated, means responsive to operation of another of said other keys to prevent energization of the motor while said other key is operated and to energize the receiver, and manual means for operating said tuning device when said motor is deenergized.
2. In a high frequency receiver having a tun-

- ing device, the combination of a motor for driving said tuning device, a plurality of keys, certain of said keys corresponding to respective frequencies to which said receiver may be tuned, and other of said keys corresponding to certain other operations to be effected, means responsive to operation of any of said certain keys to energize said motor until the receiver is tuned to a frequency corresponding to that one of said certain keys operated, and then to deenergize said motor, means responsive to operation of one of said other keys to energize said motor during the entire time during which said key is operated, means responsive to operation of another of said other keys to prevent energization of the motor while said other key is operated and to energize said motor, means mechanically to retain any of said keys except said one of said other keys in its operated position until another key is operated.
3. In a high frequency receiver having a tuning device, the combination of a motor for driv-

ing said tuning device, a plurality of keys, certain of said keys corresponding to respective frequencies to which said receiver may be tuned, and other of said keys corresponding to certain other operations to be effected, means responsive to operation of any of said certain keys to energize said motor until the receiver is tuned to a frequency corresponding to that one of said certain keys operated, and to then deenergize said motor, means responsive to operation of one of said other keys to energize said motor during the entire time when said one other key is operated, means responsive to operation of another of said keys to prevent energization of said motor while said key is operated and to energize said receiver, manual means for operating said tuning device when said motor is deenergized, means responsive to a third of said other keys to deenergize said motor and receiver, said keys being arranged in a unit including means mechanically to retain any of said keys, except said one of said other keys, in its operated position until another key is operated.

DONALD R. DE TAR.
